UNITED STATES PATENT OFFICE

ALOYSIUS W. BECKER, OF CHICAGO, ILLINOIS

DESIGN FOR A COMBINATION ASH TRAY AND GLASS HOLDER

Application filed May 1, 1933. Serial No. 47,948. Term of patent 3½ years.

To all whom it may concern:

Be it known that I, ALOYSIUS W. BECKER, a citizen of the United States, residing at Chicago, Illinois, post-office address 122 S. Michigan Ave., Chicago, Illinois, have invented a new, original, and ornamental Design for a Combination Ash Tray and Glass Holder, of which the following is a specification, reference being had to the accompanying drawing, forming part thereof.

The drawing shows a perspective view of my new design for a combination ash tray and glass holder.

I claim:

The ornamental design for a combination ash tray and glass holder as shown.

ALOYSIUS W. BECKER.
